(57) **CLAIM**

The ornamental design for a weight lifting wrist strap as shown and described.

DESCRIPTION

FIG. 1 is a perspective view of a weight lifting wrist strap;

FIG. 2 is a rear elevation view;

FIG. 3 is a front elevation view;

FIG. 4 is a bottom view;

FIG. 5 is a top view;

FIG. 6 is a right-side elevation view; and,

FIG. 7 is a left-side elevation view.

The broken line portion of the figure drawings is included to show portions of the article that form no part of the claimed design.

1 Claim, 7 Drawing Sheets
